ABSTRACT

A cartridge comprising a projectile and a cartridge case is formed with a neck at its forward end, and a sleeve-shaped holder for the projectile inserted into the mouth of the neck. A portion of the holder which is conically expanded by the insertion of the projectile bears against the inside of the neck of the cartridge case.

CARTRIDGE AND A METHOD OF PRODUCING THE SAME

BACKGROUND OF THE INVENTION

The present invention relates to a cartridge comprising a projectile and a cartridge case formed with a neck at its forward end, and a sleeve-shaped holder for the projectile inserted into the mouth of the neck.

In a conventional cartridge the sleeve-shaped holder is soldered or welded into the cylindrical mouth of the cartridge case. This method of securing the holder in the cartridge case is awkward and adversely affects the production cost of the cartridge.

BRIEF SUMMARY OF THE INVENTION

It is an object of the present invention to provide a cartridge in which the securing of the holder in the cartridge case is simpler and more reliable than in known cartridges.

According to the invention there is provided a projectile and a cartridge case formed with a neck at its forward end and a sleeve-shaped holder for the projectile inserted into the mouth of the neck, in which a portion of the holder which is conically expanded by the insertion of the projectile bears against the inside of the neck of the cartridge case.

The present invention also provides a method of assembling such a cartridge wherein the previously conically converging rear end of the holder is conically expanded when the tail end of the projectile is forced into the same.

BRIEF DESCRIPTION OF THE DRAWINGS

With the above and other objects in view which will become apparent from the detailed description below, some preferred embodiments of the invention are shown in the drawing in which:

FIG. 1 is a side view of a cartridge case with a sleeve-shaped holder in the mouth thereof shown in part sectional view;

FIG. 2 is a partial elevational view with parts in section of the arrangement showing a projectile fitted into the holder;

FIG. 3 is a partial sectional view showing the connection between the projectile and the cartridge case as in FIG. 2 at the instant the projectile is about to leave the arrangement;

FIG. 4 is an elevational view of a holder provided with holes for pressure equalization;

FIG. 5 is a similar view of a holder provided with slits for pressure equalization;

FIG. 6 is an elevational view with parts in section of an alternative embodiment of a sleeve-shaped holder in the mouth of a cartridge case; and

FIG. 7 is an elevational view with parts in section of the arrangement according to FIG. 6 with a projectile fitted therein.

DETAILED DESCRIPTION OF THE INVENTION

Referring to FIG. 1 a cartridge case 1 has a substantially cylindrical mouth 3 of smaller diameter than the remainder 2 of the case. The transition between the cylindrical mouth 3 and the substantially cylindrical remainder 2 of the case forms a conical neck 4. The cartridge case 1 contains a propellant charge 5. Inserted from the front end into the mouth of the cartridge case is a cylindrical holder 6. This holder 6 comprises a cylindrical sleeve-shaped part 7 which bears against the

cylindrical interior of the mouth 3 of the cartridge. At its forward end the cylindrical holder 6 is formed with a flange 8 which projects outwards from the cylindrical sleeve-shaped part 7. The flange 8 rests on the edge of the mouth 3 and thus prevents the holder 6 from being pushed further to the rear of the cartridge. At its rear end the cylindrical sleeve-shaped portion 7 merges into a downwardly converging frusto-conical portion 9. This rearwardly tapering portion 9 and part of the adjoining cylindrical sleeve-shaped portion 7 are situated within the rearwardly widening neck 4 of the cartridge case 1.

Referring now to FIG. 2 the cylindrical tail 11 of a projectile 10 is inserted into the cylindrical holder 6. The projectile 10 is fitted with a driving band 12 which is received into a peripheral groove 13. With the aid of this driving band 12 the projectile 10 rests firmly on the flange 8. At the rear of its tail 11 the projectile 10 is further provided with a peripheral groove 14. The sides 15 (FIG. 3) of the peripheral groove 14 diverge outwardly in the shape of a Vee. The tapering portion 9 of the sleeve-shaped holder 6 snaps into engagement with this peripheral groove 14 after having first been expanded by the cylindrical body 10 of the projectile when this is inserted. The diameter of the body 10 of the projectile in the region of the peripheral groove 14 exceeds the internal diameter of the undeformed tapering portion 9 at its narrowest point so that even after the tapering portion 9 has snapped into engagement with the peripheral groove 14 a forwardly adjoining part 16 of the holder 6 will still be conically expanded to make partial contact with the inside of the neck portion 4 of the cartridge case 1. The holder 6 as well as the projectile 10 are thus prevented from detaching themselves from the mouth of the cartridge case 1. The distance of the peripheral groove 14 from the rear edge of the driving band 12 measured in the axial direction, should be chosen to suit the length of the sleeve-shaped holder 6 to prevent the projectile 10 from having too much axial clearance between its two abutments.

FIG. 3 shows that when the projectile 10 is fired by the ignition of the charge 5 the rear part of the sleeve-shaped holder 6 will be inwardly curled over. This curled part lies between the conically widening part 16 and the conically tapering part 9 of the sleeve-shaped holder 6 (FIG. 2).

The sleeve-shaped holder 6 must be made of a material that is capable of being elastically expanded by the body of the projectile 10. Moreover, the sleeve-shaped holder 6 must always be provided with openings to admit of a rapid equalisation of pressures between the inside and outside of the wall of the holder 6 when the propellant charge is ignited. Otherwise the holder 6 might be blown out of the cartridge case 1.

In the embodiment of the sleeve-shaped holder 6 illustrated in FIG. 4 holes 17 are provided in the rearward half of the holder 6 to ensure rapid pressure equalisation.

In FIG. 5 longitudinal slits 18 have been cut into the rear edge of the wall of the holder 6 at regular peripheral intervals. The presence of these slits 18 not only ensures an equalisation of pressures, but the number and depth of the slits also limits the holding force acting on the projectile 10 to a given maximum value, and finally these longitudinal slits 18 also facilitate an elastic expansion of the conically tapering part 9 when the projectile 10 is inserted into the holder and the latter

snaps into engagement with the peripheral groove 14 in the projectile 10.

The above-described cartridge is assembled by first inserting the sleeve-shaped holder 6 into the cartridge case 1 that has been previously filled with a propellant charge 5, and by then thrusting the projectile 10 into the holder 6 until the driving band 12 strikes the flange 8 of the holder. The conically tapering part 9 of the holder 6 engages the peripheral groove 14 in the tail 11 of the projectile, whereas its conically expanded part 16 makes contact with the tapering neck 4 of the cartridge case 1. The assembly, comprising projectile 10 and holder 6, is therefore secured against becoming detached from the mouth of the cartridge case 1. Not until the round is fired can the considerable thrusts that develop fold back the conically tapering end 9 of the holder 6 to release the projectile 10. The forces which arise when the projectile 10 is released are transmitted by the rear part of the holder 6 to the neck portion 4 of the cartridge case 1. Hence the wall of the cartridge case 1 is subjected substantially exclusively to radial forces and not to forces acting in the axial direction.

In conventional connections, comprising press fits, adhesive bonding of the projectile in the mouth of the cartridge case or crimping, the forces that arise act principally in the axial direction, tending to lengthen off the mouth of the case. The mouth must therefore be of suitable length to enable it to absorb these forces.

In contradistinction thereto the mouth 3 in a cartridge according to the invention can be considerably shortened and a greater charge can therefore be accommodated in a cartridge of the same overall length-with a consequent improvement in performance. Alternatively a shorter cartridge can achieve the same performance as a conventional cartridge.

In a preferred embodiment of the invention the cartridge case 1 is made of light metal, particularly of an aluminium alloy, and the holder 6 consists of steel. The interior of the cartridge case 1 is provided with a protective coat to prevent the highly compressed propellant gases in the region of the mouth 3 of the cartridge case 1 from eroding and partly melting the alloy, when the charge is ignited. The described novel type of connection between the projectile, the holder and the cartridge case particularly ensures that this protective coat will not be damaged.

With reference to FIGS. 6 and 7 the holder 6 has a rear portion 19 that has a thickened cross section. In the unexpanded state (FIG. 6) the external diameter of the holder 6 is cylindrical, whereas the internal diameter is reduced to form a rearwardly convergent taper. When the cylindrical projectile 10 is inserted into this holder 6 the internal diameter of the holder 6 is expanded into a cylindrical shape. Consequently the external diameter of the holder 6 in this region expands to create a divergent cone which bears against the interior of the neck portion 4 of the cartridge case 1. In this arrangement the projectile 10 is held in the holder 6 in a pure press fit. I claim:

1. A cartridge comprising:

a case having a cylindrical main body portion closed at the rear end thereof and containing a propellant charge, a cylindrical mouth portion of a diameter less than the diameter of said main body portion, and a hollow frusto-conical neck portion joining said main body portion and said mouth portion;

a holder positioned within said case and having a cylindrical sleeve portion of an outer diameter to contact the interior of said mouth portion of said case, the forward end of said sleeve portion having an annular flange extending outwardly therefrom abutting the forward edge of said mouth portion of said case, the rear end of said sleeve portion merging into a flexible rearwardly converging frusto-conical portion, the length of said sleeve portion being dimensioned such that the point of juncture between said sleeve portion and said frusto-conical portion is positioned rearwardly of the juncture of said neck and mouth portions of said case when said flange abuts said edge of said mouth portion of said case; and

a projectile positioned in said holder in contact with the inner periphery of said sleeve portion, said projectile having adjacent the rear end thereof an annular groove the bottom edge of said frusto-conical portion fitting in said groove, said rear end of said projectile deforming said flexible frusto-conical portion of said holder outwardly into compression against the inner periphery of said neck portion of said case.

2. A cartridge as claimed in claim 1, wherein said projectile has an annular driving band fitted thereto, said driving band abutting the forward surface of said flange of said holder.

3. A cartridge as claimed in claim 1, wherein said frusto-conical portion of said holder has holes therein.

4. A cartridge as claimed in claim 1, wherein said frusto-conical portion of said holder has slits therein.

5. A process for assembling a cartridge comprising: providing a case having a cylindrical main body portion closed at the rear end thereof, a cylindrical mouth portion of a diameter less than the diameter of said main body portion, and a hollow frusto-conical neck portion joining said main body portion and said mouth portion; providing a holder having a cylindrical sleeve portion merging at the rear end thereof into a flexible rearwardly converging frusto-conical portion; inserting said holder, with said frusto-conical portion first, into said mouth portion of said case, such that the outer periphery of said sleeve portion of said holder contacts the inner periphery of said mouth portion of said case, and to a position such that the juncture of said sleeve portion and said frusto-conical portion of said holder is located rearwardly of the juncture between said mouth portion and said neck portion of said case; securing said holder against further displacement rearwardly into said case; inserting for a first distance into said holder a projectile with the outer periphery thereof contacting the inner periphery of said sleeve portion of said holder;

inserting said projectile a further distance into said holder, and by the rear end of said projectile forcing said flexible frusto-conical portion of said holder radially outwardly into compression with the inner surface of said neck portion of said case, thereby securing said holder against forward displacement in said case; and securing said projectile against further displacement in said holder;

6. A process as claimed in claim 5, wherein said sleeve portion of said holder has an annular flange extending outwardly from the forward end thereof, and said holder is secured against further displacement rearwardly into said case by abutting said flange against the forward edge of said mouth portion of said case.

7. A process as claimed in claim 6, wherein said projectile has an annular driving band fitted thereto, and further displacement of said projectile rearwardly into

said holder is prevented by abutting said driving band against said flange of said holder.

8. A process as claimed in claim 5, wherein said projectile has adjacent the rear end thereof an annular groove, and the bottom edge of said frusto-conical portion of said holder is engaged in said annular groove when said projectile is inserted into said holder.
